POCKET KEY AND COIN PURSE

Louis Barnett, Brooklyn, N. Y., assignor to
Louis Stern, New York, N. Y.

Application April 12, 1944, Serial No. 530,692

2 Claims. (Cl. 150—10)

1

This invention relates to pocket-books, cases or purses for use as compact containers for coins, keys or for other small articles which may otherwise be carried loosely about the person.

Among the objects of the invention is to generally improve pocket-books, cases or purses of the character described, which shall comprise few and simple parts that readily form an assembly of neat and attractive appearance, which shall be cheap to manufacture, and which shall be efficient and practical to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawing, in which are shown illustrative embodiments of this invention,

Fig. 1 is a front elevational view of a key or coin purse complete assembly constructed to embody the invention shown in a normally closed position.

Fig. 2 is a rear view of one of the front sections of the improved purse shown in Fig. 1.

Fig. 3 is a cross-sectional view taken on line 3—3 in Fig. 2.

Fig. 4 is a front elevational view of the spring element removed from the casing of the improved purse assembly.

Fig. 5 is a cross-sectional view of the complete assembly taken on line 5—5 in Fig. 1.

Figs. 6 and 7 are front and side views, respectively, showing the improved purse subjected to end compressive finger pressure for flexing the spring elements to open the closure when inserting or removing articles therefrom.

Fig. 8 is a front elevational view of a key or coin purse of modified construction embodying the invention formed with an everted casing.

Figs. 8a and 8b are cross-sectional views taken on line 8a—8a in Fig. 8 and line 8b—8b in Fig. 8a, respectively, showing the interior of the modification shown in Fig. 8, and

Fig. 9 is a cross-sectional view similar to Fig. 8a showing the everted seam joint formed with a piping or peripheral trimming.

Referring in detail to the drawing 10 denotes a key or coin pocket purse assembly constructed to embody the invention. Seen in Figs. 1 and 5, the purse 10 may be made with a casing 11 of leather or other suitable sheet material that is flexible tough wearing and lends itself to an ex-

2

terior finish which is durable in resisting frequent handling yet capable of providing a plain or ornamental surface as desired.

Said purse casing 11 may be of any suitable shape such as oval and preferably comprises a back side or section 12 and two identically shaped front sections 13. Said sections may be secured together along their peripheral edge joint by a suitable plastic adhesive, or as here shown by peripheral border stitches 14 to provide the complete casing 11 with a longitudinal abutment closure 11a extending centrally along through the front side of the purse 10 between said sections 13 for giving access to the interior of the purse. The abutment closure 11a preferably may be provided by folding back and permanently securing free edge portion 18a of each front section 13 so that the abutting folds thus formed thereon present finished reinforced rim edges 13b for said closure 11a.

Within the casing 11 and extending along the interior perimeter there is seated a pair of bowed spring elements 15. The latter may be identical structures, as shown in Fig. 4, and formed with backlooped ends 15a so as to provide rolling contact when operatively positioned, said spring elements 15 being bowed slightly but preferably less than the arcuate contour of the adjacent curvature of the interior perimeter portion of the casing 11 so that the spring elements 15 when assembled in the casing 11 are normally under tension to brace the casing structure.

The terminating ends 11b of the closure 11a may be secured together by any suitable means, such as stitches 11c, so that opposite ends 10a of the purse 10 are reinforced and provide with the underlying portions of the back side or section 12 shallow pocket portions in the casing 11 for housing in concealed position the looped spring ends 15a, said pocket portions serving to retain the spring elements ends 15a in cooperative rolling contact position at all times.

The utility of the improved purse 10 will now be apparent. After assembling the parts, as described above and shown in Figs. 1 and 5, when it is desired to open the purse 10, the opposite ends 10a thereof are compressed between the thumb and forefinger to flex the spring elements 15 with the purse casing 11 as shown in Figs. 6 and 7 whereby the front sections 13 are deflected out of their normal closed position so that the closure 11a is forced open and remains so while pressure continues to be applied.

An article, such as a key or coin, can be readily inserted or removed from the purse 10

with said closure 11a in open position. On releasing of the compressive force applied to the purse ends 10a, the spring elements 15 will act to return the casing closure 11a into effective closed position for securely retaining objects in the casing 11.

It should be noted that the spring elements 15 provide a smooth surfaced liner for the interior of the casing that is free from projecting sharp edges to eliminate possible accidentally cutting or injury to the fingers when inserted in the purse 10.

In Figs. 8, 8a, 8b and 9 modified constructions embodying the invention are shown. Here the key or coin pocket purse assembly 110, is seen to include a casing 111 which may be similar to casing 11 above described, namely, being formed of a flexible tough material suitably shaped, such as oval, and comprising a back section 112 and two identically shaped front sections 113, said sections being suitably secured together by an adhesive or stitches 114 at the peripheral border edge seam 111b of the casing 111. The front sections 113 are constructed and arranged like that shown for purse 10 with a longitudinal abutment closure 111a extending centrally along through the front side of the purse 110. Said abutment closure 111a has back folded sides permanently secured at free edge portions 113a of the front sections 113 to provide reinforced finished rim edges as shown in Figs. 8 and 8a.

Casing 111 differs in construction from casing 11 by the additional novel feature of everting the casing structure so that the border edge seam 111b is inturned, that is, casing 111 is formed with desired exterior finished surfaces thereof presented without any extending seam joints at the periphery of the purse 110. Thus the casing 111 may be first made in an "inside-out" relation and then everted for finishing the same.

Casing 111 is also provided with identically shaped bowed spring elements 115 having front-looped ends 115a, said spring elements 115 being assembled in the casing 111 in the same manner as spring elements 15 in casing 11 to provide rolling contacts and forming a smooth surfaced liner of the interior of the casing 111.

Stitches 111c are provided at opposite ends of the purse closure 111a to reinforce and provide shallow pockets in casing 111 for housing the rolling contacts of spring ends 115a.

In Fig. 9 is shown the addition of a piping or bead, 111d incorporated in the peripheral border edge seam 111b and is retained in the joint thereof by stitches 114 when the latter are used. Said piping or bead 111d serves as a trimming and makes available a large range of styles and ornaments.

The form of the invention shown in Figs. 8 and 9 when constructed as above described is used in the same manner as described above for the purse 10 for opening and closing the purse by applying pressure to the opposite ends 110a thereof as shown in Figs. 6 and 7.

It will thus be seen that there is provided means in which the several objects of this invention are achieved and which is well adapted to meet the conditions of practical use.

As various possible embodiments might be made of the above inventions, and as various changes might be made in the embodiments above set forth, it is to be understood that all

matter herein set forth or shown in the accompanying drawing is to be interpreted as illustrative and not in a limiting sense.

Having thus described my invention, I claim

5 as new and desire to secure by Letters Patent:

1. A pocket case of the character described comprising a back piece and two identically shaped front pieces forming a casing, said front pieces having integrally formed folded finished edges extending in abutment to provide a central closure, means for uniting opposite ends of said front pieces terminating said closure to form spaced pockets with the underlying portion of the back section, identically shaped spring elements extending along the perimeter of the interior of the casing, each spring element being formed with looped ends to provide a rolling contact with those of the other spring element in each pocket, the outer opposite ends of the purse casing terminating over said rolling contact spring ends serving as compression points for flexing the case to force said closure into an open position, means incorporated in said casing structure for securing said back and the front pieces together in concealed position wholly within the casing to serve as an abutment for the springs in said flexing action, and a piping trimming extending around the exterior periphery of the casing for enlarging said spring abutment on the interior of the casing retained by said securing means.

2. A pocket case of the character described, a casing formed with a back section having a self-closing opening in a front flat side thereof, said opening having reinforced finishing means extending along abutting rim edges thereof, said finishing means being integrally formed with portions of the casing along said opening, spaced pockets formed with portions of said casing back section by uniting opposite ends of said opening, identical bowed springs having looped ends extending along the perimeter of the interior of the casing for resiliently retaining the latter in an outstretched condition with said spring ends in rolling contact fitted into the pockets, outer opposite points of said casing terminating said pockets and spring ends being constructed and arranged for applying compressive force to flex the springs with the casing and separate the abutting rim edges of the opening against self closing action thereof by said springs, said casing portions and back section being secured together by a seam joint to form an everted "inside-out" structure for positioning the seam joint wholly therein to serve as an abutment for the springs in said flexing action, and a bead trim incorporated in said everted casing structure to extend through the seam joint to the exterior of the casing for enlarging said spring abutment on the interior of the casing.
